HOISTING MECHANISM

Robert C. Osgood, Claremont, N. H., assignor to
Sullivan Machinery Company, a corporation of
Massachusetts

Application October 20, 1928. Serial No. 313,904

19 Claims. (Cl. 192—4)

This invention relates to hoisting mechanisms. More particularly my invention relates to mechanism for controlling the operations of a hoist.

One object of my invention is to provide an improved mechanism for starting and stopping the winding mechanism of a hoist. A further object of my invention is to provide improved drive control mechanism for the winding mechanism of a hoist and improved brake mechanism 10 cooperating therewith. A still further object of my invention is to provide braking mechanism for a hoist which shall be automatically applied in connection with the operation of the drive control mechanism of the hoist. Other objects 15 and advantages of my invention will appear from the following description and will be further pointed out in the claims.

In the drawings,—

Fig. 1 is a side elevation of a double drum 20 hoisting mechanism which is controlled by an illustrative embodiment of my improved control mechanism.

Fig. 2 is an end view in elevation, taken from the right end of Fig. 1.

Fig. 3 is a detail view with parts broken away, showing the coaxial control shafts.

Fig. 4 is a detail view showing a brake shoe 30 cooperating with a flange of one of the drums, the brake shoe being shown in section on the line 4—4 of Fig. 5.

Fig. 5 is a detail view with parts omitted, this view showing, in end elevation, a brake shoe applied to the flange of a drum.

Fig. 6 is a fragmentary vertical sectional view 35 taken on the axis of the winding drums.

In the illustrative example shown in the drawings, the hoisting mechanism comprises a base 6 which carries a pair of supporting standards 7 and 8. A pair of drums 9 and 10 are supported 40 between standards 7 and 8. A motor 11 (herein illustrated as an electric motor) is provided to drive the winding mechanism, this motor being shown as bolted to an extension of the base 6. Driving connections are provided between the 45 motor 11 and the drums 9 and 10, these connections including reduction gearing contained in a gear box 12. The driving connections further include planetary gearing, one set of planetary gearing being provided at the outer end of each 50 drum. The nature of these sets of planetary gearing is made clear by Fig. 6, which illustrates the set of planetary gearing for the drum 10. Since the two sets are similar, a description of one set will suffice for both. The central shaft 55 40, which is driven from the motor 11 through

the reduction gearing contained in the gear box 12, is provided adjacent each end with a pinion 41. One pinion 41 is shown in Fig. 6 as meshing with a drum driver pinion 42 carried on the end of a shaft 43 which projects to the right from 60 the drum 10. An internal gear 44 completes the set of planetary gearing, the pinion 42 meshing with the internal gear 44 and rolling around within this gear as a track when the drum 10 rotates. A brake is provided to cooperate with 65 each internal gear 44, the brake 13 being adapted to hold its respective internal gear stationary to produce rotation of drum 9, and brake 14 being adapted to hold its respective internal gear stationary to produce rotation of drum 10. If, 70 on the other hand, the brake 14 be released to the position shown in Fig. 1, the corresponding internal gear will be free to rotate idly without driving the drum 10. In the same manner, the brake 13 may be released to interrupt driving 75 of the drum 9.

The brake mechanisms at the two ends of the hoist are substantially similar; and therefore a description of the brake 14, and the mechanism cooperating therewith will be sufficient to make 80 clear the operation of the entire control mechanism. The brake 14 includes a brake band 15 which cooperates with a braking surface surrounding the internal gear. A toggle mechanism 16 is operated by a control lever 17 to clamp 85 or release the brake band 15. A lever 18 is connected to the lever 17 by a connecting rod 19 pivoted to the lever 17 at 20 and to the outer end of the lever 18 at 21. The inner end of the lever 18 is secured at 22 to a hollow shaft 23 90 (see Figs. 1 and 3). The hollow shaft 23 is rotatably supported in a bearing member 32 which is secured to the base 6. It is therefore obvious that the lever 18 rocks about the axis of the shaft 23.

The operation of the above described mechanism may be controlled by a lever 25 with a handle 26, the lever 25 being secured at 27 to the hollow shaft 23. The lever 18 carries intermediate its ends a brake shoe 28. A stud 29, 100 passing through the brake shoe in the manner shown in Fig. 4, is carried by the lever 18. Once the position of the shoe 28 relative to the lever 18 is adjusted, the stud 29 secures it in this position. The brake shoe 28 cooperates with the 105 rim of the drum flange at the right end of the winding drum 10.

The operator, by grasping the handle 26, may apply the brake mechanism 14 to hold stationary the internal gear 44 at the right end of the hoist. 110

This will produce rotation of the drum 10 if the motor 11 is running. When the rope has been hauled in to the extent desired, the operator releases the brake mechanism 14 by moving the lever 25 in the opposite direction. This automatically swings the lever 18 so as to apply the brake shoe 28 to the flange of the drum 10. This prevents spinning of the drum 10. The advantage of this is obvious, since it will be apparent that the momentum acquired by the drum 10 during a paying out operation might cause it to spin, thus paying out too fast and making possible kinking of the rope and other difficulties due to a slack rope. As soon as the brake mechanism 14 is again applied to cause winding in of the rope on the drum 10, the lever 18 is automatically swung outward so as to free the drum from the brake shoe 28.

The control mechanism at the left end of the hoist, which includes the brake 13, is similar to that which has just been described in connection with the right end of the hoist, and includes a second shaft 30 which is supported in a bearing bracket 31 secured to the base 6, and also in the hollow shaft 23, which as previously described is supported in the bearing member 32. To the right end of shaft 30, which projects beyond the hollow shaft 23, an operating handle 33 is secured as shown at 34. The lever 18' at the left end of the hoist, which corresponds to the lever 18 at the right end of the hoist, is secured at 36 to the shaft 30. It is therefore obvious that the operator may station himself at the right end of the hoist and control both drums 9 and 10. It is further apparent that as soon as either brake 13 or 14 is released to interrupt driving of the corresponding drum, spinning of this drum is prevented due to the automatic application of the corresponding brake shoe to the rim of the drum flange.

While I have in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a hoisting mechanism having a drum, a motor and driving connection between the drum and motor, means for controlling the operation of said drum comprising means for braking the drum, means for applying said braking means including a lever carrying said braking means, means for controlling motor actuation of said drum including an operating lever, and a link connecting said operating lever to the lever carrying said braking means.

2. Controlling means for a hoisting mechanism having a winding drum, a motor, driving connection between said drum and motor, and a base, comprising a lever pivoted to the base, a link connected to said lever, a brake shoe for the drum carried by said lever, and means for controlling motor actuation of said drum comprising an actuating member, said link connecting said lever to said actuating member.

3. Controlling means for a hoisting mechanism having a winding drum, a motor, driving connections between said drum and motor, and a base, comprising a lever pivoted at one end to the base, a link connected to the other end of said lever, a brake shoe for the drum carried by said lever, and means for controlling motor ac-

tuation of said drum comprising an actuating member, said link connecting said lever to said actuating member.

4. In a hoisting mechanism, a drum, a driving element, gearing connecting said element and said drum including a reaction gear adapted when released to rotate without driving the drum, and when held to produce rotation of the drum, controlling means for said reaction gear comprising an actuating member, braking means for the drum oscillatable about a pivot, and a link connected to said braking means and to said actuating member. 80

5. In a hoisting mechanism, a drum, a driving element, gearing connecting said element and said drum including a reaction gear adapted when released to rotate without driving the drum, and when held to produce rotation of the drum, controlling means for said reaction gear comprising an actuating member, braking means for the drum oscillatable about a pivot, a lever for oscillating said braking means, and a link connected to said braking means and to said actuating member. 90

6. In a hoisting mechanism, a drum, a driving element, gearing connecting said element and said drum including a reaction gear adapted when released to rotate without driving the drum, and when held to produce rotation of the drum, controlling means for said reaction gear comprising a lever, braking means for the drum, means for applying said braking means comprising a shaft and means for oscillating said shaft, said braking means being secured to and supported by said shaft, and a link connecting 100 said lever to said braking means. 105

7. In a hoisting mechanism, coaxial drums, driving means therefor including drive trains whose terminal elements lie at the remote ends of the drums, means also at the opposite ends of said 115 drums controlling the transmission of power thereto by said driving means, means operatively connected with said controlling means and actuated thereby for braking each of said drums, as its respective controlling means is operated 120 to interrupt power transmission thereto, and means at one end of said drums permitting control of both said drums from that end.

8. In a hoisting mechanism, coaxial drums, journaled for rotation but confined against longitudinal movement relative to each other, driving means therefor, means at opposite ends of said drums controlling the transmission of power thereto by said driving means, means operatively connected with said controlling means and controlled and actuated thereby for automatically braking each of said drums as its respective controlling means is operated to interrupt power transmission thereto, and means at one end of said drums permitting control of both said drums 135 from that end.

9. In a hoisting mechanism, coaxial drums, driving means therefor, means at opposite ends of said drums controlling the transmission of power thereto by said driving means, means operatively connected with said controlling means and actuated thereby for braking each of said drums as its respective controlling means is operated to interrupt power transmission thereto, and operating means at one end of said drums for permitting control of both of said drums from that end, said braking means being operative to exert a braking force proportional to the braking effort applied to said operating means.

10. In a hoisting mechanism, coaxial drums,

- driving means therefor, means at opposite ends of said drums controlling the transmission of power thereto by said driving means, means operatively connected with said controlling means for braking each of said drums automatically as its respective controlling means is operated to interrupt power transmission thereto, and means for controlling both of said drums from one end including primary control elements at said end, one of said primary control elements being more remote from said drums than the other, and operative connections between said primary control elements and the power transmission control means and braking means for the drums, the operative control for said more remote primary control element connecting the latter with the power transmission control means and braking means of the drum further therefrom.
11. In a hoisting mechanism, a hoisting drum, braking means for said drum including a braking element having frictional engagement with said drum, operating means for said braking means including an element upon which said braking element is wholly supported for bodily movement relative to said drum into and out of braking position, drum driving means including a rotatable final driving element for said drum rotatable relative to the latter during drum drive and having its axis of rotation at all times at a fixed distance from the periphery of the drum, said drum driving means having a control element, and a connection between said brake operating means and said control element whereby movement of the brake operating means effects actuation of said control element to control drum drive.
12. In a hoisting mechanism, a drum, braking means therefor including a member movable to apply and release said braking means and moving in a plane, drum driving means, and a control element for said drum driving means moving in the same plane with said member.
13. In a hoisting mechanism, a drum, braking means therefor including a member movable to apply and release said braking means and moving in a plane, drum driving means, and a control element for said drum driving means moving in the same plane with said member, and a link connecting said member and element.
14. In a hoist, a winding drum, driving means therefor including a motor, and means operable while said motor is rotating for selectively establishing and interrupting a driving connection between said motor and said drum, and means for automatically braking rotation of said drum whenever the driving connection is interrupted and for automatically releasing said braking means entirely before the driving connection is established, said means for establishing and interrupting a driving connection and said braking means having a common control including an arcuately movable arm to which each is operatively connected at a point spaced from and at the same side of the arm pivot.
15. In a hoist, a winding drum, driving means therefor including a motor, a rotatable final driving element for the drum rotatable relative to
- the latter during drum drive and having its axis of rotation at all times at a fixed distance from the periphery of the drum and operating means controllable while said motor is rotating for establishing or interrupting a driving relation between the drum and motor, and means also operated by said operating means for braking rotation of said drum when driving relation between the latter and the motor is interrupted, said operating means including an element through which the driving means and the braking means are controlled and which wholly supports the braking means for bodily movement relative to the drum and which is operative to release the braking means whenever the operating means is moved to a position to establish driving relation between the drum and the motor.
16. In a hoisting mechanism, a hoisting drum, driving means for said drum including drive control means and a rotatable final driving element for said drum rotatable relative to the latter during drum drive and having its axis of rotation at all times at a fixed distance from the periphery of the drum, operating means for said drive control means, and braking means for said drum including an element carried by an element of said operating means and wholly supported thereby and actuated thereby and bodily movable into and out of braking position.
17. In a hoisting mechanism, a hoisting drum, braking means for said drum including a braking element having frictional engagement with said drum, operating means for said braking means including an element upon which said braking element is exclusively supported, the braking force imparted to said braking element being manually regulated directly through said operating means, drum driving means having a control element, and a rotatable final driving element for said drum rotatable relative to the latter during drum drive and having its axis of rotation at all times at a fixed distance from the periphery of the drum and a connection between said brake operating means and said control element whereby movement of the brake operating means effects actuation of said control element to control drum drive.
18. In a hoist, a winding drum, driving means therefor having controlling means including an arcuately movable member swingable in opposite directions on its pivot to effect drum drive and cessation of drum drive, said member being movable in a direction to increase the distance of its moving end from said drum in effecting the starting of drum drive, and braking means for said drum operatively connected with said member at a point spaced from its axis of arcuate movement.
19. In a hoisting mechanism, a drum, braking means therefor including a member movable to apply and release said braking means and moving in a plane transverse to the axis of said drum, drum driving means, and a control element for said drum driving means moving in the same plane with said member.

ROBERT C. OSGOOD.
